Des. 222,513
Patented Oct. 26, 1971

222,513

TROUSERS HANGER

Robert L. Hart, Manhasset Hills, and Marc Zuckerman and Albert Tangredi, Bayside, N.Y., assignors to W. R.
Grace & Co., Duncan, S.C.

Filed Aug. 3, 1970, Ser. No. 24,277

Term of patent 14 years

Int. Cl. D6—08

U.S. Cl. D80—8

FIG. 1

Des. 222,513

PAGE 2

FIG. 2

FIG. 3

FIG. 4

FIG. 5

FIG. 1 is a front view of a trousers hanger showing our new design.

FIG. 2 is a rear view thereof.

FIG. 3 is a right end view thereof.

FIG. 4 is a left end view thereof.

FIG. 5 is a bottom plan view thereof.

We claim:

The ornamental design for a trousers hanger, substantially as shown.
